HYDROPNEUMATIC COUNTERBALANCE

Harold Williams Ramey, Parkersburg, W. Va., assignor to The Parkersburg Rig & Reel Company, Parkersburg, W. Va., a corporation of West Virginia

Application August 8, 1938, Serial No. 223,737

24 Claims. (CL. 74—589)

This invention relates to hydropneumatic counterbalances especially adapted for use with oil well pumping rigs.

In the copending application of Robert Griffin De La Mater, Serial No. 157,189, filed August 3, 1937, there is described and claimed a particularly efficient type of hydropneumatic counterbalance particularly adapted for use with the walking beams of oil well pumping rigs. As disclosed in such copending application, it has been the common practice to counter-weight the walking beams of oil well pumping rigs to equalize the power demand throughout the pumping cycle. On the down-stroke of the rods and pump plunger, the weight suspended from the well end of the walking beam is essentially the weight of the pump rods, and on an uncounterbalanced rig, this weight would pull the beam down and thus require no power for moving the beam.

On the up-stroke of the pump rods and plunger, the weight suspended from the well end of the walking beam is essentially the weight of the rods plus the weight of the fluid being lifted. With an uncounterbalanced pumping rig the prime mover is required to furnish all of the power necessary for lifting such total weight. As a result it is obvious that the power cycle would be very uneven in an uncounterbalanced rig, the power varying from negative to positive and being greatly affected by other forces such as inertia, etc.

In counterbalancing an oil pumping rig, it is the common practice to provide counterbalancing approximating the extent of the weight of the pump rods, plus half the weight of the fluid lifted on each up-stroke of the pump rods. Thus on the down-stroke, the weight of the counterbalance is greater than the weight of the pump rods, the difference being approximately equal to one-half the weight of the fluid lifted on each up-stroke of the pump rods. On the up-stroke the counterbalance, which was raised on the down-stroke, balances off the weight of the pump rods, plus half the weight of the liquid being lifted, and accordingly the weight required to be lifted by the prime mover and half the weight of the liquid on each of the strokes of the pump rods.

Until the development of the construction disclosed in the copending application referred to, the walking beams of oil well pumping rigs were commonly counterbalanced in either of two ways, namely, by counter-weighting the walking beam itself or by counter-weighting the crank shaft from which the pitman is driven. Each of these systems possesses advantages which are offset by

substantial disadvantages. For example, the theoretically ideal position for providing the counterbalancing is at the well end of the walking beam, which point is close to the point of application of loads to the walking beam. This arrangement, however, is disadvantageous because of the great amount of weight which must be mounted on the beam, the inertia of the weights at the top and bottom of the pumping stroke being so great as to require a beam of substantial construction to support the loads to which it is subjected. There are further disadvantages to the counter-weighting of the walking beam which are discussed in the copending application referred to and need not be described in detail in connection with the present invention.

Rotary crank weights have been more extensively used with beam weights because of certain inherent advantages which they possess. For example, less damage results in case of a failure of the pitman or pump rods and it is far more convenient to handle the beam when the pitman is disconnected therefrom. Moreover, rotary counter-weights are more readily adjusted for lag and lead, and they always maintain the pitman in tension instead of alternately in tension and under compression. However, rotary crank weights are far from easily adjustable, in spite of their advantage over beam weights, substantial difficulties being encountered in handling and adjusting the weights. It also is obvious that rotary counter-weights add substantial loads to the crank and crank shaft.

Having in mind the disadvantages inherent in weight counterbalancing, numerous efforts have been made to provide counterbalancing by pneumatic means which operates to store energy on the down stroke of the pump rods and to expend energy on the up-stroke. Such a mechanism involves numerous advantages over conventional counter-weighting in that it permits the application of the counterbalancing force substantially at the ideal point while eliminating the use of heavy masses of weights on the walking beam or crank shaft. Thus the pumping equipment is more portable and more easily installed, and requires less foundation for stability.

However, pneumatic counterbalances also have been found in practice to involve numerous disadvantages. Such disadvantages are discussed in the copending application referred to and the construction shown therein has been highly efficient in operation with all of the inherent advantages of prior systems without any of their disadvantages. In the structure of the prior

application referred to, a plunger is mounted to reciprocate in a cylinder having a lower end communicating with a receiver of substantial volume, the plunger being pivotally connected at its upper 5 end to the walking beam, and the cylinder-receiver unit being pivotally connected at its lower end to the foundation of the rig. The receiver is provided with a body of a non-compressible fluid such as oil which is displaceable from the lower 10 end of the cylinder on each down stroke of the plunger to compress air or other compressible gas entrapped in the receiver above the level of the oil. The quantity of the oil is variable for providing different counterbalancing actions, but 15 sufficient oil is maintained in the receiver so that the level of the oil is never below the lower end of the cylinder. Accordingly it is impossible for any of the entrapped air to enter the lower end of the cylinder to leak past the plunger, and accordingly 20 such construction provides no problem as to air leakage.

The quantity of the oil employed may be varied in accordance with the desired differential between minimum and maximum pressures in the 25 receiver according to the particular installation, which is a result not obtainable with weight counterbalances or pneumatic counterbalances. Automatic means is provided for maintaining the desired quantity of oil in the receiver to maintain 30 a predetermined maximum pressure therein. Such automatic means is desirable because of minor leakages of oil past the plunger, and to compensate for expansion and contraction incident to temperature changes.

35 The automatic means referred to comprises a pump connected between an oil reservoir and the receiver and preferably operated by the horizontal component of movement in the receiver incident to swinging movement of the walking beam. A 40 blow off valve is provided between the pump and the receiver to permit pumped oil to be by-passed to the reservoir instead of being passed to the receiver so long as the maximum pressure is maintained in the latter, the blow off valve being adjustable 45 to determine the blow off pressure. Thus a practicable counterbalancing mechanism is provided which operates efficiently over long periods of time without any attention on the part of the operator.

50 In my copending application Serial No. 163,862 filed September 14, 1937, I have disclosed a counterbalance of the same type as the counterbalance disclosed in the application of Robert Griffin De La Mater referred to, which provides 55 several additional advantageous features. For example my co-pending application discloses means operable after the receiver has been charged with air under pressure for maintaining a partial vacuum in the cylinder above the plunger 60 to thus provide increased differential pressures on opposite sides of the plunger without increasing the pressure of the fluids in the receiver above the pressure of the atmosphere. The mechanisms of my copending application and the application of Robert Griffin De La Mater are similar in theory of operation and practicability.

I have found that in certain locations in which 65 mechanisms of this character are employed, the temperature changes throughout each twenty-four hours are sufficiently small so as to cause negligible changes in pressures in the receiver incident to expansion and contraction. In such locations, it is not nearly so important to provide automatic means for guarding against pressure 70 changes incident to temperature variations, and

accordingly it is desirable to simplify the apparatus by eliminating the automatic means necessary for by-passing oil from the pump to the reservoir. The elimination of such automatic means obviously reduces the cost of manufacture 5 of the apparatus and reduces installation and maintenance costs.

Accordingly an important object of the present invention is to provide a novel hydropneumatic counterbalance operating on the same principles 10 as the counterbalances of the copending applications referred to wherein pressure conditions within the receiver are maintained within relatively narrow limits, except for temperature variations, without the use of automatic means associated with the oil pump, as disclosed in the copending applications referred to.

A further object is to provide a hydropneumatic counterbalance particularly adapted for use in locations where temperature conditions vary between 20 relatively close minimum and maximum temperatures, and wherein gradual leakage of oil past the counterbalance plunger is compensated for to maintain pressures in the receiver within relatively narrow limits.

25 A further object is to provide means for preventing the loss of oil or other non-compressible fluid from the system whereby the level of the oil in the reservoir may be employed as the controlling factor in determining the supplying of oil to the receiver to maintain a constant quantity of oil therein and thus maintain the desired pressures in the receiver between relatively close limits.

30 A further object is to provide means for returning 35 to the reservoir any oil which leaks past the counterbalance plunger to prevent any loss of oil from the system, and to provide means controlled by the level of the oil in the reservoir for determining the effectiveness of the oil pump for supplying oil to the receiver whereby a constant 40 quantity of oil may be maintained therein.

A further object is to provide a mechanism of the character referred to wherein the inlet pipe of the oil pump is connected to the receiver below 45 the normal level of the oil therein, and to provide float controlled means for such pipe to admit oil to the pump to be injected into the receiver when the level of the oil in the reservoir rises above a predetermined point incident to the returning 50 thereto of oil leaking past the counterbalance plunger, and to cut off the supply of oil to the pump when the level of the oil in the reservoir is at or below such predetermined point.

55 A further object is to provide a direct connection between the top portion of the cylinder and the reservoir for returning to the latter oil which leaks past the plunger, and to provide means above the packing gland through which the plunger rod reciprocates at the top of the cylinder 60 for collecting any oil which is wiped from the plunger rod upon each downward stroke thereof, to return such oil to the reservoir, thereby preventing any loss of oil from the system and rendering it practicable to determine the effectiveness 65 of the pump for supplying oil to the receiver in accordance with the level of the oil in the reservoir.

70 Other objects and advantages of the invention will become apparent during the course of the following description.

In the drawing I have shown one embodiment of the invention. In this showing:

75 Figure 1 is a side elevation of a standard well rig showing the invention connected thereto,

Figure 2 is a schematic sectional view of the counterbalance system as a whole, parts being shown in elevation, and,

5 Figure 3 is an enlarged detail sectional view of the upper end of the cylinder showing the oil collecting means associated with the packing gland.

10 Referring to Figure 1 the numeral 10 designates a conventional walking beam mounted as at 11 to oscillate upon the upper end of a conventional Samson post 12. The walking beam is oscillated in the usual manner by a pitman 13 driven by a crank 14 mounted upon a crank shaft 15 to be driven by the usual prime mover, not 15 shown. The well end of the beam is connected by the usual polished rod carrier 16 and the usual pump or polished rods 17. A conventional apparatus of this character is provided with "headache posts" to prevent damage to the apparatus and injury to workmen in the event of 20 breakage of any part of the apparatus. The present construction, as is true of the structures of the co-pending applications referred to, functions to permit the elimination of the usual headache posts by limiting swinging movement of the 25 walking beam 10.

For the purpose of illustration, the present invention has been shown as applied to a conventional type of pumping rig. It will be apparent, 30 however, that it is capable of application to any analogous structure.

The present invention comprises a counterbalance unit indicated as a whole by the numeral 18, comprising a receiver 19 having upper and 35 lower heads 20 and 21 preferably welded to the body of the receiver. A supporting member 22 is preferably welded to the lower head 21 and is pivoted as at 23 to a suitable support 24 mounted on the foundation 25 of the pumping rig.

40 The head 20 is provided with an axial opening 26 surrounded by a relatively heavy flange 27 welded in position on the head 20 concentric with the opening 26. A cylinder 28 projects downwardly through the opening 26 into the receiver and is provided adjacent its upper end with an annular enlarged portion 29 fitting within the flange 27, the cylinder being provided above the portion 29 with an outstanding annular flange 30 bolted as at 31 to the flange 27. 45 A bearing 32 is mounted in the upper end of the cylinder and is provided with a suitable bushing 33. The bearing 32 is provided at its upper end with an outstanding annular flange 34 seating upon the upper end of the cylinder and bolted thereto as at 35. The bearing 32 is provided intermediate its ends with a clearance space 36 communicating at its lower end through grooves 37 with the interior of the cylinder, the bearing 32 otherwise being in tight fitting engagement 50 with the upper end of the cylinder 28.

As more clearly shown in Figure 3, packing means is provided to minimize as completely as possible any leakage of oil past the bushing 33. A plate 38 is bolted as at 39 to the upper end 55 of the bearing 32 and seats against a packing ring 40 surrounding a plunger rod 41 which reciprocates in the bushing 33, the plunger rod being pivotally connected at its upper end to the walking beam as at 41' and being provided 60 at its lower end with a plunger 42 reciprocating in the cylinder 28. The packing ring 40 engages compressible packing 43 surrounding the plunger rod as clearly shown in Figure 3.

The upper end of the cylinder is provided with 65 an annular recess 44 and the flange 34 is radially

drilled as at 45 to provide a passage communicating with the space 44. The upper face of the plate 38 is provided with a conical recess 46, and drainage openings 47 communicate between the recess 46 and the space 44. Accordingly oil wiped 5 from the plunger rod upon downward movement thereof will collect in the recess 46 to be drained through the openings 47 into the space 44, from which the oil is drained through the radial opening 45 for a purpose to be described.

10 The receiver is adapted to contain a body of oil or other non-compressible fluid as indicated by the numeral 48, the space 49 above the oil being charged with air or other compressible gas under pressure. Plugs 50 are tapped into the 15 wall of the receiver as shown in Figure 2 to facilitate the charging of the receiver with oil and for determining the level of the oil therein, the oil level preferably being determined when the plunger 42 is at its lower limit of movement. 20

For the purpose of maintaining the proper volume of oil in the receiver a pump is adapted to operate at all times during the operation of the walking beam, although it will become apparent that any other suitable type of pumping 25 means may be employed. The pump is indicated as a whole by the numeral 51 and comprises a cylinder 52 in which is arranged a plunger 53. The cylinder 52 may be maintained stationary in a manner to be described while the plunger 53 is 30 preferably pivotally connected as at 54 to the receiver 19 to be operated by the horizontal component of movement of the receiver incident to swinging movement of the walking beam 10. The opening in which the pivot pin 54 is arranged may have sufficient play therein to compensate for the very slight vertical component of movement existing between the adjacent portion 35 of the receiver and the plunger 53.

Oil is supplied to the pump 51 from a reservoir 40 58 which is vented to the atmosphere as at 59. The level of the oil in the reservoir may be as indicated by the line 60. A pipe 61 is connected between the bottom of the reservoir and the cylinder 52 and is provided with a suitable check 45 valve 63 to permit the flow of oil into the pump and to prevent the oil from flowing from the pump to the reservoir as will be understood. A suitable stationary support 64 is provided for the reservoir 58, and also may be employed for 50 rigidly supporting the pump cylinder 52.

The pipe 61 extends through the bottom of the reservoir to communicate with an outlet pipe 65 the upper end of which is adapted to be closed by a valve 66 carried by an arm 67 pivotally connected as at 68 to an arm 69 carried by the pipe 65, the free end of the arm 69 being provided with a float 70. It will be apparent that when the level 60 of the oil in the reservoir raises above the point indicated, the float 70 will open 60 the valve 66 and admit oil to the pump. When the level of the oil in the reservoir is as low as the point 60 the supply of oil to the pump will be cut off and the pump will be rendered ineffective for supplying oil to the receiver. When the 65 pump is functioning incident to the opening of the valve 66 it will pump oil through a flexible outlet pipe 71 and thence through a rigid pipe 72 to the bottom of the receiver, the pipe 72 being provided with a check valve 73 functioning as a 70 part of the pump to permit oil to flow only in one direction, namely, from the pump to the receiver. A pressure gage 74 is preferably connected in the pipe 72 between the valve 73 and the receiver. 75

Referring to Figure 2, the numeral 75 designates a pipe connected at one end to the top of the reservoir 58 and at its opposite end to one end of a flexible pipe connection 76, the other end of this connection leading to a pipe 77 tapped into the opening 45. A check valve 78 is arranged in the pipe 77 and permits the flow of fluid therethrough only from the space 36 toward the reservoir 58. A three-way valve 79 is arranged between the valve 78 and the passage 45 and is normally arranged in a position to provide communication straight through the pipe 77. However, the three-way valve, under conditions to be described, may be moved to a second position disconnecting the passage 45 from the valve 78 and connecting it to a check valve 80 leading to the atmosphere and operative for admitting air into the passage 45. A pipe 81 is connected between the passage 45 and the pipe 77 outwardly of the check valve 78.

The cylinder is provided with a second radial passage 82, extending through the flange 30, as shown in Figure 2, and a pipe 83 is connected between the passage 82 and the receiver 19 adjacent the top thereof. Two check valves 84 and 85 are arranged in the pipe 83. These check valves function to prevent the escape of pressure from the top of the receiver during the normal operation of the apparatus. While one check valve is sufficient for the operation of the apparatus, it is preferred that two be employed in order to completely eliminate any escape of air from the top of the receiver.

The operation of the apparatus is as follows:

When the operation of the apparatus is to be started, oil may be supplied to the receiver to the desired level in accordance with the preferred counterbalancing action to be provided in a given installation. For example, with the plunger 42 in its lower position, oil may be filled to the level of the lower plug 50, whereupon this plug may be replaced. Oil is likewise supplied to the reservoir 58 to the level indicated by the line 60, that is, to the highest depth at which the valve 66 will remain closed. In other words, the oil in the receiver having been placed at the desired level, the level of the oil in the reservoir is at such point that any elevation in such level will result in supplying additional oil to the receiver, as will become apparent.

With the system charged with oil in the manner stated, the three-way valve 79 is turned to the position in which the passage 45 communicates with the check valve 80, which is inwardly opening as previously stated.

The operation of the prime mover is now initiated to oscillate the walking beam. Upon each downward movement of the plunger 42, air will be drawn into the upper end of the cylinder 28 through the check valve 80, three-way valve 79 and passage 45. Upon each upward movement of the plunger 42, air in the upper end of the cylinder will be compressed and discharged through the pipe 83 to the air space 49 in the receiver. This operation is continued until the air space 49 is charged with compressible fluid at the desired pressure. The three-way valve 79 is then moved to its other position disconnecting the passage 45 from the check valve 80 and connecting it to the check valve 78, which opens outwardly with respect to the passage 45.

When the full desired pressure in the receiver is attained in the manner described, the system becomes fully operative as a counterbalance.

Upon each downward stroke of the plunger 42,

the oil or other non-compressible fluid will be displaced from the lower end of the cylinder 28 into the receiver 19, thus raising the level of the oil in the receiver against the downward pressure exerted by the compressible fluid in the space 49. The pressure in the latter space increases progressively upon the progressive downward movement of the pump rods and reaches its maximum pressure when the pump rods reach their lowermost position. Thus it will be apparent that energy is stored in the body of the trapped compressed fluid in the space 49, which energy is expended on the up-stroke of the pump rods to assume part of the load of the pump rods and the oil being lifted from the well. Thus the prime mover is required to perform only a portion of the work incident to the elevation of the pump rods. As previously stated, the counterbalance preferably exerts an upward force equal to the weight of the pump rods plus half the weight of the column of oil being lifted, and at least at the beginning of the up-stroke therefore, the force exerted by the prime mover is the force necessary to elevate half the weight of the column of oil being lifted. Thus it will be apparent that in accordance with the disclosures of the copending applications referred to, the present construction provides a highly efficient counter-balancing action, the force required to compress the fluid in the space 49 on the down-stroke of the pump rods being greater than the weight of the pump rods, thus requiring that the prime mover exert substantial force in moving the pump rods to their lower position. The work performed by the prime mover is approximately equal to the work performed by the prime mover during the up-stroke of the pump rods, thus rendering far more uniform the power demands which are made on the prime mover throughout each complete cycle of operation.

It will be apparent that the present construction adds nothing to the weight of the walking beam and thus permits the use of a much lighter walking beam than is possible in installations wherein counterweighting is connected to the walking beam itself. Moreover, the counterbalance applies the counterbalancing force at a point close to the point at which the work is performed, thus being highly advantageous over the use of crank counterbalances. The apparatus possesses a greater degree of flexibility than crank counterbalances, as will be explained, and the down-stroke of the plunger is limited whereby the device, upon the breakage of the pitman, performs the function of the usual headache post.

As stated above, the counterbalance is highly flexible in its operation and any desired counterbalancing action may be provided. For example, by using relatively small amounts of oil in the receiver 19, the difference between minimum and maximum pressures may be made as small as desired. On the other hand, far greater differences in minimum and maximum pressures may be provided by increasing the amount of oil in the counterbalance. It also will be apparent that the desired minimum and maximum pressures will be predetermined by the extent to which the space 49 is charged with air upon the initial operation of the apparatus, it merely being necessary to hold the valve 79 in the charging position until the desired pressure in the receiver is reached.

The present apparatus is particularly intended for localities in which there is no great change in temperature conditions throughout each twen-

ty-four hour period, under which conditions pressure changes in the receiver incident to expansion and contraction will be minimized. For example, in some localities temperatures are so nearly constant that there will be not more than 5 lb. variation in pressure in the receiver above and below the theoretically correct pressure. Therefore, the present apparatus is intended to be employed where it is not necessary to automatically compensate for pressure changes in the receiver incident to changing temperature conditions, and accordingly the automatic pressure charging means of the copending applications referred to is eliminated.

15 However, while leakage of compressible fluid from the receiver is prevented, there will be a slow or continued leakage of oil past the plunger 42 and past the bushing 33 and if such leakage is permitted to continue over substantial periods 20 of time it necessarily follows that there will be progressive lowering of the pressures in the receiver. The present apparatus is particularly intended to prevent the occurrence of drops in pressure in the receiver incident to the leakage 25 of oil in the manner stated.

It will be noted that the space 36 surrounding the bearing 32 extends above the passage 45, and accordingly the upwardly extending portion of the space 36 forms a compression space to prevent the upper end of the cylinder from becoming completely filled with the non-compressible fluid, thus resulting in the inevitable breakage of the apparatus.

As oil leaks past the plunger 42, it gradually collects on the upper face of the plunger and when the level of the oil above the plunger moves upwardly as far as the passage 45 upon each up-stroke of the plunger, the latter element acts as a pump to discharge the oil through the passage 45, pipe 77, check valve 78 and pipes 76 and 15 to return the oil to the reservoir. Of course, a film of oil will be maintained on the plunger rod 41 to lubricate the bearing bushing 33, and upon each down-stroke of the plunger rod, a small quantity of the oil will be wiped from the plunger rod by the inner edge of the plate 38. The wiped oil will collect in the recess 46 and will drain through the openings 47 into the recess 44, from which it will be discharged by gravity through the pipe 81 to be returned to the reservoir.

Thus it will be apparent that while a small quantity of oil will necessarily constantly leak past the plunger 42, none of this oil is lost but all of it is returned to the reservoir. The returning of such oil to the reservoir gradually raises the level of the oil therein, and when the oil level in the reservoir raises slightly above the point 60, the float 70 will unseat sufficiently to permit the drainage of some of the oil from the reservoir into the pump inlet pipe 61.

65 It will be apparent that the walking beam oscillates about its pivot 11 and since the pivot 41, through which the plunger rod 41 is reciprocated, swings on an arc of a circle concentric with the pivot mounting 11 of the walking beam, the receiver will have a small horizontal component of movement during oscillation of the walking beam. Such horizontal movement is employed for constantly reciprocating the pump plunger 53 as long as the walking beam oscillates. Whenever the valve 66 is unseated incident to the raising of the level of the oil in the reservoir in the manner desired, oil will flow through the pipe 75 61 into the pump cylinder 52 and will be dis-

charged through pipes 71 and 72 into the receiver. The amount of oil which will be supplied to the pump is always exactly equal to the amount of oil which has leaked past the plunger and accordingly a constant quantity of oil will be maintained in the receiver. 5

The foregoing functions form the most important features of the present invention. While the level of the oil in the receiver changes constantly during the operation of the walking beam, incident to reciprocation of the plunger 42, the parts described function to maintain a constant quantity of oil in the receiver. Since leakage of air from the space 49 cannot occur, and since the leakage of oil from the receiver is exactly compensated for, it will be apparent that the apparatus will operate constantly between the desired predetermined minimum and maximum pressures for which the apparatus has been set.

If for any reason it is desired to increase the amount of oil in the receiver to step up the initially created pressures therein, additional oil may be supplied to the receiver, whereupon the raising of the level of the oil in the reservoir will result in the unseating of the valve 66. Accordingly a quantity of oil exactly equaling the amount added to the reservoir will be pumped to the receiver to increase pressures therein. If it is desired to somewhat reduce pressures in the receiver oil may be withdrawn in any desired manner from the receiver 58, whereupon the gradual leakage of oil past the plunger 42 will merely reduce pressures in the receiver until the level of the oil in the reservoir is restored to the point indicated by the numeral 60. Thus it will be apparent that the quantity of oil permitted to be ultimately discharged from the receiver will exactly equal the quantity of oil withdrawn from the reservoir.

As previously stated, the present apparatus is 40 particularly intended for use in localities in which no great differences in temperature occur throughout each twenty-four hour period. Thus the apparatus permits the elimination of the relatively expensive blow-off valve shown in each of the prior applications referred to for controlling pressures in the receiver. The present apparatus requires the use of no pressure responsive valves of any type and yet operates to maintain constant pressures in the receiver, such pressures 45 varying solely through differences in temperature conditions in the locality in which the apparatus is employed. 50

When the apparatus is initially charged with air the valve 79 opens the passage 45 to the check valve 80, as stated. When the desired pressure in the space 49 is reached, the apparatus is preferably stopped with the plunger 42 at its upper limit of movement, whereupon the valve 79 is turned to its normal position closing communication between the passage 40 and the check valve 80. Accordingly no further air will be admitted to the upper end of the cylinder, and a partial vacuum will be created upon each downward movement of the plunger 42. Thus the apparatus permits the utilization of increased differential pressures between the space 49 and the space above the plunger 42, without further increasing the pressures of the fluids in the receiver above atmospheric pressure. This feature of the apparatus forms no part of the present invention per se, but is described and claimed in my co-pending application referred to. 70

It is to be understood that the form of the invention herewith shown and described is to be 75

taken as a preferred example of the same and that various changes in the shape, size and arrangement of parts may be resorted to without departing from the spirit of the invention or the scope of the subjoined claims.

5 I claim:

1. A counterbalance for parts having uniform relative movement, comprising a compression chamber, a hollow member, a fluid displacing member movable in said hollow member, said compression chamber having relatively unrestricted communication with said hollow member, a body of a non-compressible fluid at least partially filling said compression chamber and extending into said hollow member to be displaced therefrom by said displacing member, and means for replenishing the non-compressible fluid in accordance with the leakage of such fluid from the counterbalance.
- 10 2. A counterbalance for parts having uniform relative movement, comprising a compression chamber, a hollow member, a fluid displacing member movable in said hollow member, said compression chamber having relatively unrestricted communication with said hollow member, a body of a non-compressible fluid at least partially filling said compression chamber and extending into said hollow member to be displaced therefrom by said displacing member, and means for replenishing the non-compressible fluid in accordance with the leakage of such fluid from the counterbalance.
- 15 3. A counterbalance comprising a compression chamber, a hollow member, a fluid displacing member movable in said hollow member and operable from a point externally of said compression chamber and said hollow member, said compression chamber communicating with said hollow member, a body of a non-compressible fluid at least partially filling said compression chamber and extending into said hollow member to be displaced therefrom by said displacing member, a receptacle, means for transferring to said receptacle non-compressible fluid leaking from said hollow member, and means controlled by the level of the non-compressible fluid in said receptacle for supplying to said compression chamber non-compressible fluid in amounts equal to the amounts of the leakage of such fluid from said hollow member.
- 20 4. A counterbalance comprising a compression chamber, a hollow member, a fluid displacing member movable in said hollow member and operable from a point externally of said compression chamber and said hollow member, said compression chamber communicating with said hollow member, a body of a non-compressible fluid at least partially filling said compression chamber and extending into said hollow member to be displaced therefrom by said displacing member, a receptacle containing a body of a non-compressible fluid to a predetermined level, a pump having its inlet connected to said receptacle and its outlet connected to said compression chamber, a float in said receptacle closing said inlet when the level of the non-compressible fluid in such receptacle is at or below said predetermined level and operable for admitting non-compressible fluid to said inlet when the fluid raises above said predetermined level, and means for returning to said receptacle non-compressible fluid leaking from said hollow member.
- 25 5. A counterbalance for parts having uniform relative movement, comprising a compression chamber, a cylinder having substantially unrestricted communication at its lower end with said compression chamber, a plunger reciprocable in said cylinder and projecting from the upper end thereof, a body of a non-compressible fluid at least partially filling said compression chamber and displaceable from the lower end of said cylinder upon downward movement of said plunger, and means for replenishing the non-compressible fluid in accordance with the leakage of such fluid from the counterbalance.
- 30 6. A counterbalance for parts having uniform relative movement comprising a compression chamber, a cylinder having substantially unrestricted communication at its lower end with said compression chamber, a plunger reciprocable in said cylinder and projecting from the upper end thereof, a body of a non-compressible fluid at least partially filling said compression chamber and displaceable from the lower end of said cylinder upon downward movement of said plunger, and means for supplying non-compressible fluid to said compression chamber, said means being operable in accordance with the amounts of non-compressible fluid leaking past said plunger.
- 35 7. A counterbalance comprising a compression chamber, a cylinder communicating at its lower end with said compression chamber, a plunger reciprocable in said cylinder and projecting from the upper end thereof, a body of a non-compressible fluid at least partially filling said compression chamber and displaceable from the lower end of said cylinder upon downward movement of said plunger, means for collecting non-compressible fluid leaking past said plunger, and means controlled in accordance with the amount of leakage fluid collected for supplying an equal amount of non-compressible fluid to said compression chamber.
- 40 8. A counterbalance comprising a compression chamber, a cylinder communicating at its lower end with said compression chamber, a plunger reciprocable in said cylinder and projecting from the upper end thereof, a body of a non-compressible fluid at least partially filling said compression chamber and displaceable from the lower end of said cylinder upon downward movement of said plunger, a receptacle containing a body of a non-compressible fluid, means for collecting non-compressible fluid leaking past said plunger and returning it to said receptacle, and means for transferring non-compressible fluid from said receptacle to said body of non-compressible fluid, said last named means being controlled in accordance with the amounts of leakage fluid returned to said receptacle.
- 45 9. A counterbalance comprising a compression chamber, a cylinder communicating at its lower end with said compression chamber, a plunger reciprocable in said cylinder and projecting from the upper end thereof, a body of a non-compressible fluid at least partially filling said compression chamber and displaceable from the lower end of said cylinder upon downward movement of said plunger, a receptacle containing a body of a non-compressible fluid, means for collecting non-compressible fluid leaking past said plunger and returning it to said receptacle, a pump having its inlet connected to said receptacle and its outlet to said compression chamber, and means for admitting non-compressible fluid from said receptacle to said pump in accordance with the amounts of leakage fluid returned to said receptacle.

10. A counterbalance comprising a compression chamber, a cylinder communicating at its lower end with said compression chamber, a plunger reciprocable in said cylinder and projecting from the upper end thereof, a body of a non-compressible fluid at least partially filling said compression chamber and displaceable from the lower end of said cylinder upon downward movement of said plunger, a receptacle containing a body of a non-compressible fluid to a predetermined level, a pump having its inlet connected to said receptacle and its outlet connected to said compression chamber, a float having a valve connected therewith closing said inlet when the level of the non-compressible fluid in said receptacle is at or below said predetermined level, said float being operable for opening said valve to admit fluid to said pump when the non-compressible fluid in said receptacle rises above said predetermined level, and means for returning to said receptacle non-compressible fluid leaking from said cylinder.

11. A counterbalance comprising a compression chamber closed to the atmosphere and containing compressible fluid under pressure, a cylinder having its lower end communicating with said compression chamber, a plunger reciprocable in said cylinder, a body of a non-compressible fluid in said compression chamber displaceable from said cylinder upon downward movement of said plunger, the amount of said non-compressible fluid being sufficient to form a seal between said compressible fluid and the lower end of said cylinder, a receptacle containing non-compressible fluid to a predetermined level, means for returning from the upper end of said cylinder to said receptacle non-compressible fluid leaking past said plunger, a bearing in the upper end of said cylinder in which said plunger reciprocates, means for returning to said receptacle non-compressible fluid collecting on said bearing from said plunger, and means for supplying from said receptacle to said compression chamber non-compressible fluid in amounts equal to the amounts of non-compressible fluid returned to said receptacle.

12. A counterbalance comprising a compression chamber closed to the atmosphere and containing compressible fluid under pressure, a cylinder having its lower end communicating with said compression chamber, a plunger reciprocable in said cylinder, a body of a non-compressible fluid in said compression chamber displaceable from said cylinder upon downward movement of said plunger, the amount of said non-compressible fluid being sufficient to form a seal between said compressible fluid and the lower end of said cylinder, a receptacle containing non-compressible fluid to a predetermined level, means for returning from the upper end of said cylinder to said receptacle non-compressible fluid leaking past said plunger, a bearing in the upper end of said cylinder in which said plunger reciprocates, means for returning to said receptacle non-compressible fluid collecting on said bearing from said plunger, a pump connected between said receptacle and said compression chamber, and means for controlling said pump to render it effective for transferring from said receptacle to said compression chamber non-compressible fluid in amounts equal to the amounts of non-compressible fluid returned to said receptacle.

13. A counterbalance comprising a compression chamber closed to the atmosphere and con-

taining compressible fluid under pressure, a cylinder having its lower end communicating with said compression chamber, a plunger reciprocable in said cylinder, a body of a non-compressible fluid in said compression chamber displaceable from said cylinder upon downward movement of said plunger, the amount of said non-compressible fluid being sufficient to form a seal between said compressible fluid and the lower end of said cylinder, a receptacle containing non-compressible fluid to a predetermined level, means for returning from the upper end of said cylinder to said receptacle non-compressible fluid leaking past said plunger, a bearing in the upper end of said cylinder in which said plunger reciprocates, means for returning to said receptacle non-compressible fluid collecting on said bearing from said plunger, a pump connected between said receptacle and said compression chamber, and means including a float in said receptacle controlled by the level of the non-compressible fluid therein for rendering said pump effective for transferring from said receptacle to said compression chamber non-compressible fluid in amounts equal to the amounts of non-compressible fluid returned to said receptacle.

14. A counterbalance comprising a compression chamber closed to the atmosphere and containing compressible fluid under pressure, a cylinder having its lower end communicating with said compression chamber, a plunger reciprocable in said cylinder, a body of a non-compressible fluid in said compression chamber displaceable from said cylinder upon downward movement of said plunger, the amount of said non-compressible fluid being sufficient to form a seal between said compressible fluid and the lower end of said cylinder, a receptacle containing non-compressible fluid to a predetermined level, means for returning from the upper end of said cylinder to said receptacle non-compressible fluid leaking past said plunger, a bearing in the upper end of said cylinder in which said plunger reciprocates, means for returning to said receptacle non-compressible fluid collecting on said bearing from said plunger, a pump having its inlet connected to said receptacle and its outlet to said compression chamber, a valve in said receptacle controlling said inlet, and a float in said receptacle controlling said valve to admit non-compressible fluid from said receptacle to said pump to be injected into said compression chamber when the level of the non-compressible fluid in said receptacle rises above a predetermined point.

15. A counterbalance comprising a compression chamber, a substantially vertical cylinder communicating at its lower end with said compression chamber, a plunger reciprocable in said cylinder and having a plunger rod projecting from the upper end thereof, a bearing in the upper end of said cylinder surrounding said plunger rod, a body of a non-compressible fluid in said compression chamber, said compression chamber containing compressible fluid under pressure adapted to be compressed by said non-compressible fluid upon displacement thereof from the lower end of said cylinder when said plunger moves downwardly, a receptacle, a conduit connecting said cylinder above the upper limit of movement of said plunger to said receptacle to return to the latter non-compressible fluid leaking past said plunger, means for collecting non-compressible fluid from said plunger rod above

- 5 said bearing and returning it to said receptacle, and means for transferring from said receptacle to said compression chamber non-compressible fluid in amounts equal to the amounts of non-compressible fluid returned to said receptacle by said conduit and by said collecting means.
- 10 16. A counterbalance comprising a compression chamber, a substantially vertical cylinder communicating at its lower end with said compression chamber, a plunger reciprocable in said cylinder and having a plunger rod projecting from the upper end thereof, a bearing in the upper end of said cylinder surrounding said plunger rod, a body of a non-compressible fluid in said compression chamber, said compression chamber containing compressible fluid under pressure adapted to be compressed by said non-compressible fluid upon displacement thereof from the lower end of said cylinder when said plunger
- 15 moves downwardly, a receptacle, a conduit connecting said cylinder above the upper limit of movement of said plunger to said receptacle to return to the latter non-compressible fluid leaking past said plunger, means for collecting non-compressible fluid from said plunger rod above said bearing and returning it to said receptacle, and means for transferring from said receptacle to said compression chamber non-compressible fluid in amounts equal to the amounts of non-compressible fluid returned to said receptacle by said conduit and by said collecting means, said last named means comprising a pump having its inlet connected to said receptacle and its outlet connected to said compression chamber, and
- 20 35 float controlled means in said receptacle for determining the admission of non-compressible fluid from said receptacle to said pump in accordance with the rate of return of non-compressible fluid to said receptacle by said conduit and by said collecting means.
- 25 17. A counterbalance comprising a compression chamber closed to the atmosphere, a substantially vertical cylinder communicating at its lower end with said compression chamber, a plunger reciprocable in said cylinder and having an upwardly extending plunger rod, a bearing mounted in the upper end of said cylinder and surrounding said plunger rod, said compression chamber containing a body of a non-compressible fluid in the bottom thereof and being charged above said non-compressible fluid with compressible fluid under pressure, said non-compressible fluid being displaceable from the lower end of said cylinder upon downward movement of said plunger to compress said compressible fluid, a receptacle containing non-compressible fluid to a predetermined level, a conduit affording communication between said receptacle and said cylinder above said plunger when the latter is at its upper limit of movement to return to said receptacle non-compressible fluid leaking past said plunger, the upper face of said bearing being provided with a recess surrounding said plunger rod to receive therefrom non-compressible fluid leaking past said bearing, a conduit for returning non-compressible fluid from said receptacle to said compression chamber, and means for transferring from said receptacle to said compression chamber non-compressible fluid in amounts equal to the amounts of non-compressible fluid returned to said receptacle by said conduits.
- 30 40 18. A counterbalance comprising a compression chamber closed to the atmosphere, a substantially vertical cylinder communicating at its lower end with said compression chamber, a plunger reciprocable in said cylinder and having an upwardly extending plunger rod, a bearing mounted in the upper end of said cylinder and surrounding said plunger rod, said compression chamber containing a body of a non-compressible fluid in the bottom thereof and being charged above said non-compressible fluid with compressible fluid under pressure, said non-compressible fluid being displaceable from the lower end of said cylinder upon downward movement of said plunger to compress said compressible fluid, a receptacle containing non-compressible fluid to a predetermined level, a conduit affording communication between said receptacle and said cylinder above said plunger when the latter is at its upper limit of movement to return to said receptacle non-compressible fluid leaking past said plunger, the upper face of said bearing being provided with a recess surrounding said plunger rod to receive therefrom non-compressible fluid leaking past said bearing, a conduit for returning non-compressible fluid from said receptacle to said compression chamber, and means for transferring from said receptacle to said compression chamber non-compressible fluid in amounts equal to the amounts of non-compressible fluid returned to said receptacle by said conduits.
- 45 50 55 60 65 70 75 19. A counterbalance for parts having uniform relative movement, comprising a compression chamber, a hollow member, a fluid displacing member movable in said hollow member, said compression chamber having relatively unrestricted communication with said hollow member, a body of a non-compressible fluid at least partially filling said compression chamber and extending into said hollow member to be displaced therefrom by said displacing member, means for supplying non-compressible fluid to said body of non-compressible fluid, and means for controlling said last named means in accordance with the leakage of non-compressible fluid from the counterbalance.
- 55 60 65 70 75 19. A counterbalance for parts having uniform relative movement, comprising a compression chamber, a hollow member, a fluid displacing member movable in said hollow member, said compression chamber having relatively unrestricted communication with said hollow member, a body of a non-compressible fluid at least partially filling said compression chamber and extending into said hollow member to be displaced therefrom by said displacing member, and means for collecting non-compressible fluid leaking from the counterbalance, the counterbalance having means for returning non-compressible fluid from said last named means to said body of non-compressible fluid.
- 70 75 21. A counterbalance for a member having uniform relative movement, comprising a pair of structures one of which is connected to said member and the other of which is connected to a stationary support, one of said members comprising a cylinder and the other comprising a plunger reciprocable in said cylinder and operative for displacing fluid therefrom upon movement of said member in one direction, the counterbalance having a compression chamber into which fluid is displaced from said cylinder by said plunger, the counterbalance containing a

reciprocable in said cylinder and having an upwardly extending plunger rod, a bearing mounted in the upper end of said cylinder and surrounding said plunger rod, said compression chamber containing a body of a non-compressible fluid in the bottom thereof and being charged above said non-compressible fluid with compressible fluid under pressure, said non-compressible fluid being displaceable from the lower end of said cylinder upon downward movement of said plunger to compress said compressible fluid, a receptacle containing non-compressible fluid to a predetermined level, a conduit affording communication between said receptacle and said cylinder above said plunger when the latter is at its upper limit of movement to return to said receptacle non-compressible fluid leaking past said plunger, the upper face of said bearing being provided with a recess surrounding said plunger rod to receive therefrom non-compressible fluid leaking past said bearing, a conduit for returning non-compressible fluid from said receptacle to said compression chamber, and means for transferring from said receptacle to said compression chamber non-compressible fluid in amounts equal to the amounts of non-compressible fluid returned to said receptacle by said conduits, said last named means comprising a pump having its inlet connected to said receptacle and its outlet connected to said compression chamber, and float controlled means for admitting to said inlet oil collecting in said receptacle above said predetermined level.

20 25 30 35 40 45 50 55 60 65 70 75 19. A counterbalance for parts having uniform relative movement, comprising a compression chamber, a hollow member, a fluid displacing member movable in said hollow member, said compression chamber having relatively unrestricted communication with said hollow member, a body of a non-compressible fluid at least partially filling said compression chamber and extending into said hollow member to be displaced therefrom by said displacing member, means for supplying non-compressible fluid to said body of non-compressible fluid, and means for controlling said last named means in accordance with the leakage of non-compressible fluid from the counterbalance.

20 25 30 35 40 45 50 55 60 65 70 75 19. A counterbalance for parts having uniform relative movement, comprising a compression chamber, a hollow member, a fluid displacing member movable in said hollow member, said compression chamber having relatively unrestricted communication with said hollow member, a body of a non-compressible fluid at least partially filling said compression chamber and extending into said hollow member to be displaced therefrom by said displacing member, and means for collecting non-compressible fluid leaking from the counterbalance, the counterbalance having means for returning non-compressible fluid from said last named means to said body of non-compressible fluid.

20 25 30 35 40 45 50 55 60 65 70 75 21. A counterbalance for a member having uniform relative movement, comprising a pair of structures one of which is connected to said member and the other of which is connected to a stationary support, one of said members comprising a cylinder and the other comprising a plunger reciprocable in said cylinder and operative for displacing fluid therefrom upon movement of said member in one direction, the counterbalance having a compression chamber into which fluid is displaced from said cylinder by said plunger, the counterbalance containing a

body of a non-compressible fluid at least partially filling said compression chamber and sealing a body of a compressible fluid therein, and means for replenishing the non-compressible fluid in accordance with the leakage of such fluid from the counterbalance.

22. A counterbalance for a member having uniform relative movement, comprising a pair of structures one of which is connected to said member and the other of which is connected to a stationary support, one of said members comprising a cylinder and the other comprising a plunger reciprocable in said cylinder and operative for displacing fluid therefrom upon movement of said member in one direction, one of said structures having a compression chamber into which fluid is displaced from said cylinder by said plunger, the counterbalance containing a body of a non-compressible fluid at least partially filling said compression chamber and sealing a body of a compressible fluid therein, and means for replenishing the non-compressible fluid in accordance with the leakage of such fluid from the counterbalance.

23. A counterbalance for parts having uniform relative movement, comprising a compression chamber, a hollow member, a fluid displacing member movable in said hollow member, said compression chamber having relatively unre-

stricted communication with said hollow member, a body of a non-compressible fluid at least partially filling said compression chamber and extending into said hollow member to be displaced therefrom by said displacing member, and means automatically controlled in accordance with the amounts of leakage of non-compressible fluid from the counterbalance for replenishing the non-compressible fluid in the counterbalance.

24. A counterbalance for a member having uniform relative movement, comprising a pair of structures one of which is connected to said member and the other of which is connected to a stationary support, one of said members comprising a cylinder and the other comprising a plunger reciprocable in said cylinder and operative for displacing fluid therefrom upon movement of said member in one direction, one of said structures having a compression chamber into which fluid is displaced from said cylinder by said plunger, the counterbalance containing a body of a non-compressible fluid at least partially filling said compression chamber and sealing a body of compressible fluid therein, and means automatically controlled in accordance with the amounts of leakage of non-compressible fluid from the counterbalance for replenishing the non-compressible fluid in the counterbalance.

HAROLD WILLIAMS RAMEY.
